SYSTEM FOR STARTING SYNCHRONOUS
TELEGRAPH MOTORS

Louis M. Poits, Evanston, Ill., assignor to Teletype Corporation, Chicago, Ill., a corporation of Delaware

Application September 2, 1939, Serial No. 293,160

7 Claims. (Cl. 179—3)

The present invention pertains to telegraph systems and particularly to combination telegraph and telephone systems.

An object of the invention is the provision of a system wherein synchronism between a driving motor of a substation telegraph apparatus and a driving motor of the central office telegraph equipment is maintained by transmitting alternating currents from the central office over a communication line, independently of telegraph communication signals concurrently transmitted over the line.

A further object of the invention is to start a telegraph substation synchronous motor by direct current supplied from the central office and thereafter to maintain such motor in synchronous rotation by alternating currents.

A further object of the invention is to use line conductors for telegraph signals and for motor power concurrently.

A feature of the invention is to provide on one telephone line two independent circuits for telegraph operation, the said two circuits being either conductively independent or conductively dependent but operatively independent, then to use one of said circuits for maintaining a telegraph motor in synchronous rotation with a central office motor, and to use the other of said circuits for telegraph communication, utilizing further a portion of the telegraph communication circuit for a short period for starting the telegraph motor at the substation.

A further feature of the invention is the provision of manually operable means at the central office by which an operator at the central office, having seized a line by switching means, may change the circuit conditions of the seized line to motor starting condition and subsequently to telegraph transmission condition.

To attain the noted features and objects, a telephone line having usual substation and central office telephone equipment is provided further with substation telegraph equipment including a receiving recorder, a relay responsive to control from the central office and a motor which may be driven in continuous rotation by alternating current and which may be started by direct current.

For controlling the substation equipment, according to one embodiment of the invention, central office apparatus cooperates with substation apparatus to form a motor power circuit over one line conductor and a telegraph signaling circuit over another line conductor. In absence of energizing conditions for the noted substation

relay, the telegraph signaling circuit is converted by contacts of the unenergized relay into a motor starting circuit for direct current and after the motor has been started by direct current over the signaling conductor, a source of alternating current may be connected to the motor power circuit, energizing the motor to run continuously and energizing the substation relay to operate its armature, thus forming the telegraph signaling circuit through contacts of the energized relay and including the receiving recorder therein.

When the combination telephone and telegraph line is idle, it may be seized for use for telephone service or for telegraph service, but while the line is in use for telephone service, additional contacts on the telephone hook switch remove the telegraph equipment from association with the line conductors, and while the line is in use for telegraph service, the telephone equipment of the substation is disabled by contacts in the substation relay.

The substation telegraph motor when thus started runs in synchronism with a continuously operating central office telegraph motor which is driven from the same source of alternating power current.

In modified structures embodying the invention, the motor power path may be a grounded phantom circuit formed from the two sides of a physical metallic telegraph signaling circuit, an axially shiftable motor armature may be provided with switching contacts to effect the functions of the substation relay, or a polar relay in the telegraph signaling circuit may replace the noted alternating current substation relay, current in one polar sense being supplied at the central office to control the polar relay to form a motor starting circuit at the substation and current in the other polar sense being supplied at the central office to control the polar relay to form a telegraph signaling circuit including the recording receiver at the substation.

A more complete understanding of the invention will be obtained from the following description, taken in connection with the accompanying drawing, in which like numerals indicate like parts and in which,

Fig. 1 illustrates a telephone substation apparatus and central office controlling apparatus providing conductively separate circuits for motor power and for telegraph signaling with ground return;

Fig. 2 illustrates a system embodying a phan-

tom circuit for motor power and a metallic circuit for telegraph signaling;

Fig. 3 illustrates a modification of the system of Fig. 1 with polar control for forming a motor starting circuit;

Fig. 4 illustrates a modification of the system of Fig. 2 in which the motor armature effects the functions of the alternating current relay of Fig. 2;

Fig. 5 shows a modification applicable to any of the illustrated systems should it be desired to transmit telegraph signals of alternating current or of resonant nature; and

Fig. 6 illustrates switching equipment of the telephone system for interconnecting telephone lines for telephonic communication.

In general, all telephone lines served by jacks as 1, 2, 3, 4 in a telephone exchange may be interconnected for telephone communication by connective links as 5, Fig. 6. In such a telephone exchange, any substation telephone set, as 6, 7, 8 and 9, may have added thereto a telegraph set which may be connected to the telephone line conductors through contacts in the telephone hook switch which may be closed when the telephone is not in use and when the telephone receiver is on the hook. Thus, telephone operators at the central office may call the telephone set into operation by ringing its bridging bell as 10 or telegraph operators at the central office may call the telegraph set into operation by starting its driving motor 11. Telegraph equipment at the central office is provided in the form of a plug as 12 which may be inserted in any telephone jack as 1 to engage a line, each such plug being provided with a manual key as 13 for setting up motor starting conditions for the substation motor 11, and each operator being provided with a transmitter 14 of design to control a substation recorder 21, a home recorder 15, and a continuously rotating driving motor 16.

According to the system illustrated in Fig. 1, the substation 20 has a telegraph recorder 21 driven by a motor 11, the motor comprising field magnets N, S, a synchronous winding or alternating current winding 22 connected to feed rings 23, and a divided or direct current starting winding 24 connected to segments of commutator 25. The synchronous winding 22 is connected from ground through condenser 26, winding of alternating current relay 27 and hook switch contacts 28 to the upper conductor of the line 29, while the starting winding 24 is connected from ground through back contacts of relay 27 and hook switch contacts 28 to the lower conductor of the line 29. The telegraph recorder 21, symbolized by its selector magnet, is connected from ground to front contacts of relay 27. Contacts in relay 27 shunt the contacts 28 when the relay 27 is operated and a further contact 31 in relay 27 opens the circuits of the telephone bell 10 and of the induction coil winding 30 when the relay 27 is operated.

At the central office, the tip of plug 12 is connected through normally closed contacts of key 13 to alternating current generator 35 and the ring of plug 12 is connected through recorder magnet 15, transmitter contacts 14 and battery 36 to ground. The ring of plug 12 is further connected to a normally open contact of key 13, a cooperating contact being connected to battery 37. Battery 38 is connected to the body member of plug 12 to supply current through jack 1 for energizing and operating the cutoff relay 39 to disconnect the signaling equipments 40 and 41. 75

Motor 16 is driven continuously by generator 35 over an obvious circuit.

In operation, according to the system illustrated in Fig. 1, the operator at the telegraph set comprising transmitter 14 and recorder 15 inserts plug 12 in jack 1 and operates key 13 manually. Battery 38 operates relay 39 and battery 37 starts motor 11 and drives it up to synchronous speed or higher by current over a circuit including battery 37, closed contacts of operated key 13, ring of plug 12, lower conductor of line 29, upper hook switch contacts 28, back contacts of deenergized relay 27, commutator 25 and starting winding 24 to ground. Upon release of key 13, a normal motor driving circuit is formed including generator 35, contacts of key 13 now normal, tip of plug 12, upper conductor of line 29, lower hook switch contacts 28, winding of relay 27, condenser 26, feed rings 23 and driving winding 22 of motor 11 to ground. Relay 27 attracts its armature and connects recorder magnets 21 to form the definitive telegraph signaling circuit including battery 36, transmitter 14, recorder 15, plug 12, jack 1, line 29, hook switch contacts 28, front contacts of operated relay 27 and recorder magnet 21 to ground. The telephone set 6 now is disabled by contact 31 of relay 27 which opens the circuit of induction coil winding 30 and of bell 10, at the same time removing the bell 10 from recorder magnet 21 as a shunt. Substation recorder 21 now is responsive to operator's transmitter 14 and a home record at the central office is produced by recorder 15. Should it be desired that telegraph transmission be effected by alternating current, a generator as 42, Fig. 5, may be associated with transmitter 14 in place of battery 36.

In Fig. 2 there is shown a modification of the structure of Fig. 1 for metallic loop telegraph signaling. A driving circuit for substation motor 51 is formed when plug 52 is inserted in jack 2 and includes generator 53, phantoming differentials 54 in parallel, inner contacts in parallel in key 55, plug 52, jack 2, conductors in parallel in line 56, hook switch contacts 57 in parallel, phantoming condensers 58 in parallel, winding of alternating current relay 59, and synchronous driving winding 60 of motor 51 to ground. Current in the described circuit energizes relay 59 to form a metallic loop telegraph signaling circuit including battery 61, transmitter contacts 63, home recorder magnet 62, winding 44 of an inductive bridging coil 44-45, upper contact and switching spring of key 55, tip members of plug 52 and jack 2, upper conductor of line 56, upper pair of hook switch contacts 57, substation recorder magnets 64, contacts of operated relay 59, lower pair of hook switch contacts 57, lower conductor of line 56, ring members of jack 2 and plug 52, lower switch spring and inner contact of key 55, and winding 45 of bridging coil 44-45, to battery 61. Contacts 52 in relay 59 disable the telephone set 7 by opening the circuit of the induction coil winding 34 and bell 33, at the same time removing the bell 33 from the recorder magnet 64 as a shunt. Operation of key 55 effects a starting circuit for motor 51 by opening the described driving circuit to deenergize relay 59. A starting circuit then is formed comprising a metallic loop from battery 65 and ground through both of the outer contacts of operated key 55, plug 52, jack 2, line 56, contacts 57, back contacts of deenergized relay 59, and starting winding 66 of motor 51.

Operation of the structure illustrated in Fig. 2

is similar to that of Fig. 1, in that the operator inserts plug 52 and operates key 55 during a time period sufficient to permit motor 51 to reach operating speed, when by release of key 55 the described starting circuit is interrupted and the described driving circuit is formed, resultantly energizing the relay 59 to complete the described metallic loop telegraph signaling circuit.

Fig. 3 illustrates a structure in which one conductor of the telephone line 70 is utilized to form a grounded driving circuit for substation motor 71 and the other conductor of line 70 is utilized to form a grounded telegraph signaling circuit, a substation motor control relay 72 being controlled in polar manner by reversal of current in the telegraph signaling conductor instead of by current in the driving circuit as shown in relay 27, Fig. 1, and relay 59, Fig. 2.

In operation of the structure of Fig. 3, beginning by insertion of switching plug 73 in jack 3, a definitive driving circuit is formed including generator 74, ring members of plug 73 and jack 3, lower conductor of line 70 upper hook switch contacts 75, driving winding 76 of substation motor 71, condenser 77 and ground. By operation of manual key 78, a starting battery 79 having its negative pole grounded, is connected to complete a starting circuit including polar battery 79, contact of key 78, tip members of plug 73 and jack 3, upper conductor of line 70, lower contacts 75, winding of polar relay 72, contacts of relay 72, starting winding 80 of motor 71 and ground. Polar sense of current through winding of relay 72 is such as to retain the armature in the position illustrated. Release of key 78 leaves motor 71 operating under power from generator 74. Reclosure of the inner contact of key 78 permits a current from battery 82, having its positive pole grounded, through home recorded magnet 83, transmitter contacts 81, contacts of key 78, tip members of plug 73 and jack 3, upper conductor of line 70, lower contacts 75, winding of relay 72 and to contacts of relay 72, whence an initial portion of the current flows through starting winding 80 to ground, the relay 72 immediately responding to the reversal of polarity of current to reverse the relay armature, after which the circuit is extended from contacts of relay 72 through substation recorder magnet 84 to earth. Reversal of contacts 88 of relay 72 opens the circuit of the telephone bell 86 and induction coil winding 87. Condenser 85 forms a shunt around the winding of relay 72 for telegraph signal currents.

In the structure illustrated in Fig. 4, the armature of a substation motor 90 is utilized to effect functions of an electromagnetic relay, by providing a mechanical spring 91 pressing against the end of the armature shaft 92 of the motor and capable of moving the shaft axially when no current flows in any winding of the armature. Contact springs 93 are controlled by spring 91 and are open when no current flows in any armature winding. Contact springs 89 are controlled by spring 91 and are closed when no current flows in the armature.

Operation of the structure illustrated in Fig. 4 is begun by inserting plug 94 in jack 4, completing a phantom driving circuit for motor 90 including generator 95, differential phantoming inductances 96, inner contacts and switching springs of manual key 97, plug 94, jack 4, both conductors of line 98, hook switch contacts 99, phantoming condensers 100, driving winding 101 and ground. Motor 90 does not start, but by

magnetic effect of current in the described circuit the armature windings cooperate with the pole faces of the motor to move the armature shaft axially against tension of spring 91 and thus cause contacts 93 to close together. Operation of manual key 97 now interrupts the described current in the driving circuit and replaces the magnetic effect in the motor to hold contacts 93 closed by supplying a motor starting current in a metallic loop starting circuit which includes battery 102 and ground, both of the outer contacts, and both switching springs of key 97, plug 94, jack 4, both conductors of line 98, hook switch contacts 99, starting winding 103, and substation recorder magnets 104. Upon release of manual key 97, the described driving circuit is restored and motor 90 now continues in rotation, also holding closed the contacts 93 and holding open the contacts 89. Telegraph signaling is over a metallic loop circuit including battery 105, transmitter contacts 107, recorder magnets 106, winding 107 of an inductive bridging coil 107-108, upper inner contact and upper switching spring of key 97, tip members of plug 94 and jack 4, upper conductor of line 98, upper pair of hook switch contacts 99, starting winding 103, closed contacts 93, recorder magnet 104, lower pair of contacts 99, lower conductor of line 98, ring members of jack 4 and plug 94, lower switching spring and lower inner contact of key 97 and winding 108 of coil 107-108 to battery 105. The starting winding is shunted by condenser 108. Contacts 99 hold open the telegraph circuits when the telephone is in use and contacts 89 hold open the circuits of induction coil winding 109 and bell 110 when the telegraph is in use.

The invention has been illustrated herein by embodiment in specific structures, but it is to be considered as accurately described only by the spirit and scope of the appended claims.

What is claimed is:

1. In a signaling system, central office apparatus, telephone and telegraph substation apparatus, a line connecting said substation apparatus and said central office apparatus, a motor included in said substation apparatus, a starting winding in said motor, a driving winding in said motor, a starting circuit including said starting winding, a driving circuit including said driving winding, a manual key included in said central office apparatus having key contacts in said starting circuit and in said driving circuit connected to close said circuits alternatively, and means effective through the operation of said key to render said telegraph apparatus effective and said telephone apparatus ineffective.

2. The combination claimed in claim 1, in which said starting circuit is a metallic circuit and in which said driving circuit is a phantom circuit.

3. In a combined telephone and telegraph system, a telephone line, a telephone set connected to said line, a telegraph set including a driving motor connected to said line, a driving circuit for said motor, a starting circuit for said motor, a relay responsive to motor-driving current having a winding included in said driving circuit and having contacts included in said starting circuit, said contacts connected to open said starting circuit in response to driving current in said winding in said driving circuit, and a manually operable key having key contacts in said driving circuit and further key contacts in said starting circuit, said key contacts and said further key contacts being alternatively closable by said key to close

alternatively said driving circuit or said starting circuit.

4. The combination claimed in claim 3, in which said starting circuit is a metallic circuit and in which said driving circuit is a phantom circuit.

5. In a telegraph system, a substation, telegraph apparatus including a driving motor and a control magnet at the substation, a central station, a circuit connecting the substation to the central station, means operated by one polarity of current transmitted from the central station over the circuit to connect the circuit to the motor and operable by the other polarity of current to connect the circuit to the control magnet.

6. In a telegraph system, a telegraph circuit, 15 telegraph apparatus including a motor and a control magnet at one end of the circuit, telegraph apparatus at the other end of the circuit, means to apply motor starting current to the circuit at the last mentioned end of the circuit and to disconnect the motor starting current and apply signaling current to the circuit, means at the first

end responsive to said current to control the connection of the motor to the circuit, and means included in the second mentioned means to disconnect the motor and connect the circuit to the control magnet.

7. In a telegraph system, a telegraph circuit, telegraph apparatus including a motor and a control magnet at one end of the circuit, telegraph apparatus at the other end of the circuit, means to apply motor starting current to the circuit at the last mentioned end of the circuit and to disconnect the motor starting current and apply signaling current to the circuit, means at the first end responsive to said current to control the connection of the motor to the circuit, means included in the second mentioned means to disconnect the motor and connect the circuit to the control magnet, and means to supply other current to the motor thereafter to maintain its speed.
